Patented Oct. 26, 1971

222,491

TOY AMPHIBIOUS VEHICLE

Arthur R. Gorfain, Fair Lawn, N.J., assignor to
Cragstan Industries, Inc., New York, N.Y.

Filed Apr. 15, 1970, Ser. No. 22,441

Term of patent 14 years

Int. Cl. D21—01

U.S. Cl. D34—15

FIG. 2

FIG. 1

Des. 222,491

PAGE 2

FIG. 3

FIG. 4

FIG. 5

FIG. 6

FIG. 7

FIG. 1 is a front perspective view of a toy amphibious vehicle showing my new design;

FIG. 2 is a rear perspective view thereof;

FIG. 3 is a side elevational view thereof;

FIG. 4 is a front elevational view of FIG. 1 on a reduced scale;

FIG. 5 is a rear elevational view of FIG. 1 on a reduced scale;

FIG. 6 is a top plan view thereof; and

FIG. 7 is a bottom plan view thereof.

I claim:

The ornamental design for a toy amphibious vehicle, substantially as shown and described.
